United States Patent Office.

JOSEPH W. GRAY, OF CLERMONT COUNTY, OHIO, ASSIGNOR TO SALADEE, FEE, AND COMPANY.

Letters Patent No. 76,322, dated April 7, 1868.

IMPROVEMENT IN STEAM-ENGINE GOVERNOR.

The Schedule referred to in these Letters Patent and making part of the same.

TO ALL WHOM IT MAY CONCERN:

Be it known that I, JOSEPH W. GRAY, of the county of Clermont, in the State of Ohio, have invented a new and improved Mode of Constructing a Combined Steam-Gauge and Governor; and I hereby declare that the following is a full and exact description thereof; reference being had to the accompanying drawings, and the letters of reference marked thereon.

The nature of my invention consists chiefly in the manner hereinafter shown and described of combining, in one arrangement of parts, a steam-gauge and governor, in such manner that the pressure of steam in the boiler will govern the engine.

In the drawings, J represents a small cylinder, secured to the top of the boiler N, at any convenient point, by means of bolts and the flanch P. This cylinder J is provided with a piston-rod, K, on the lower end of which is the piston-head O, closely fitting the cylinder J. The top of the cylinder is provided with a suitable cap or head, through which the piston-rod is allowed to work, the same as in the cylinder and piston of a steam-engine. To the top of the piston-rod, K is hinged, in any proper manner, the short connecting-plate I, at the line 7, which is hinged to the lever A A 1, at dotted line 6. To the cylinder J is cast solid, or otherwise secured, the frame E F, substantially as shown in the drawing. The left side of this frame F is made to receive and hold the lever A, so as to work upon a joint, as shown at H. The right side of the frame E is made to form the dial for indicating the pressure of the steam in the boiler. This dial is provided with the band D, the lower end of which has a series of small cogs, C, which I represent by the blue shading. These cogs, C, mesh into a corresponding series of cogs, B, represented in blue shading, on the rear end of the lever A. The spiral spring V has one end secured to the frame F, at 9, and the other to the lever A, at 8, for the purpose of drawing down the lever as the steam in the boiler diminishes in power. A weight may be substituted for the spring V, and answer the same purpose equally well. The lever A extends beyond the bearing at H, as shown at A 1, in the outer end of which is hinged, at R, the rod or "stretcher" S, which connects the valve of the engine at X.

The operation of this combination of steam-gauge and governor is substantially as follows, viz: We will suppose that the engine is now working, with the valve wide open, with a pressure of but thirty pounds of steam, as indicated upon the gauge-dial E, and that this, for example, is the pressure we desire to maintain upon the engine. It will now be observed that as the steam rises in the boiler, the piston K, in the cylinder J, will be raised accordingly, and push up the rear end of the lever A, which being connected to the band D by cogs B and C, will indicate upon the dial E the increased pressure of the steam, while at the same time the outer end of the lever at R is correspondingly lowered, and by means of the connecting-rod S the valve X is acted upon. Thus, if the steam rises to indicate, say fifty pounds, when we want but a pressure of thirty pounds upon the engine, with the valve wide open, the valve will be closed so as to admit of but thirty pounds' pressure. For as the steam raises the end A of the lever, by the upward pressure of the piston K, and indicates the same upon the dial, as already shown and described, the end A 1 of the lever is lowered, and the valve acted upon accordingly, and a uniform pressure of steam maintained upon the engine.

Having thus fully described the nature and object of my invention, what I claim as new, and desire to secure by a grant of Letters Patent, is—

The combination of a steam-gauge and governor, so constructed and arranged that the pressure of the steam in the boiler shall govern the engine, substantially as shown and described.

In testimony that I claim the above, I hereto subscribe my name, on this 25th day of April, 1867.

JOSEPH W. GRAY.
